UNITED STATES PATENT OFFICE.

SAMUEL ANDREW McFARLAND, OF OAK PARK, ILLINOIS.

OVERLAY-CUTTING MACHINE.

Application filed November 15, 1924. Serial No. 750,185.

My invention relates to an overlay cutting machine, especially adapted to operate on, cut or slice off the raised portions appearing on the coated side of an overlay sheet, the main object of the invention being to provide a machine of this character which will be efficient in operation, and which will greatly reduce the expense, time and labor ordinarily involved in "making ready" printing forms.

Other objects will appear hereinafter.

The invention consists in the combinations and arrangements of parts hereinafter described and claimed.

The invention will be best understood by reference to the accompanying drawings forming a part of this specification, and in which,

Fig. 1 is an end elevational view of a machine made in accordance with the present invention, a portion of the base being shown as broken away;

Fig. 2 shows a front elevational view of the machine with a portion of the base broken away;

Fig. 3 shows a cross sectional view, taken substantially on the line 3—3 of Fig. 2;

Fig. 4 is a view of a portion of the machine as it appears from the rear, this view illustrating in particular the bands for holding the overlay sheet in position during its downward movement on the cylinder;

Fig. 5 is a vertical section taken on the line 5—5 of Fig. 2;

Fig. 6 is a vertical section taken on the line 6—6 of Fig. 5; and

Fig. 7 is an enlarged view of a fragment of the coated overlay sheet, showing especially the raised impressions which appear on the coated side of the sheet.

In "making ready" printing forms, considerable skill and experience are essential and much time is consumed. No form or engraving is so perfectly true and level that when inked in it will show a clear and perfect impression. Accordingly, the form must be increased here and reduced there until part of it will show its true value clearly, distinctly and sharply. If the "make-ready" is inadequate, there is a lack of clearness and the effect is indistinct. In order to obtain adequate "make-ready", it is a common practice to build up the "low spots" by adding slips of paper. My present machine is employed in connection with

the converse of this method. Instead of compensating for inequalities in the forms by adding slips of paper to the "low spots" I tear down or slice off the "high spots" or impressions which appear on the coated sides of coated overlay sheets. The present machine therefore has for its primary purpose the provision of means whereby quickly and accurately to cut or slice off the high points or raised portions appearing on the coated sides of overlay sheets.

The preferred form of my machine as illustrated in the accompanying drawings comprises an elongated hollow base 8, upon the opposite ends of which are bolted inverted V-shaped end frames 9 in the top portions of which is rotatably mounted a main driving shaft 10 having mounted thereon between the end members 9 a cylinder 11 formed with raised ends or flanges 12. This cylinder 11 is ground accurately so that all portions of its circumference will be of uniform distance from its central axis. Adjacent the end frames 9 at the inner sides thereof are solid end frames 13 which are pierced by the main driving shaft 10. For the purpose of operating on the coated overlay sheets when they are applied to the cylinder 11 I provide for adjustment towards and away from the circumference of the cylinder the cutting tools 14, of which there are three illustrated in the accompanying drawings. Each of these cutting tools 14 has a central axis 15, the opposite ends of which are rotatably mounted in journal boxes 16 which slide upon ribs or keys 17 provided in the solid end members 13, the arrangement of these parts being such that the cutting tools may be moved towards or drawn away from the surface of the cylinder accordingly as the journal boxes are moved. For the purpose of adjusting the cutting tools relatively to the cylinder there is attached to the forward side of each journal box a plate 18 behind which a disc member 19 has turning fit. Each disc member 19 represents the end of an adjusting screw 20, the forward portion of which has threaded engagement in a supporting member 21 which is secured by screws 22 or otherwise to the front face of the end member to which it belongs. Each adjusting screw is furnished with a knurled turning disc 23 whereby to be adjusted by hand; and adapted to engage upon a plain portion 24, formed

on each adjusting screw is a locking screw 25 which is tapped through a reduced portion 26 on the supporting member 21, the purpose of the locking screw being to lock the adjusting screw in its adjusted position. Each of the cutting tools 14 is provided with a plurality of spirally extending cutting knives 27. In the present embodiment these cutting knives are shown as produced integrally with the cutting tools, although they may if desired be made as separate parts. Preferably, these cutting knives do not extend in the same spiral direction on the several cutting tools. Thus in Fig. 2 of the accompanying drawings it will be observed that the spirally coursing knives on the middle cutting tool extend in a direction opposite to the spiral courses of the knives on the top and bottom cutting tools.

By making the cutting tools with spirally extending cutting knives, these instruments have in operation a slicing action, since they have angular relation with respect to the central axis of the cylinder. As will be presently seen these cutting tools are all driven in the same direction but in a direction opposite to the rotation of the cylinder. By making the spirally extending knives on one cutting tool so that they course in a direction opposite to the spiral course of the knives on the other cutting tools, the "high points" on the overlay sheets are severed or sliced cleanly and positively by being attacked in opposite directions. From what has been said, it will be understood that each of the cutting tools is adjustable independently of the others, so that they may all be given an equal adjustment with respect to the cylinder, or so that, if desired each may be adjusted differently with respect to the cylinder.

The main driving shaft at one end extends beyond the supporting end 9 where it is equipped with a driving pulley 28 adapted to receive any suitable driving belt (not shown). This driving pulley is also provided with a handle 29 so that the machine may be operated by hand. At the end of the machine opposite the driving pulley, the driving shaft is provided with a large driving gear 30 which is in mesh with the smaller intermediate gears 31 of which there is of course one for each cutting tool. Each of these intermediate gears is mounted upon a stud post or shaft 32 which projects from the end frame 13. Each of the intermediate gears 31 operates a still smaller gear 33 which is fastened on the end of the cutting tool axis 15. In view of this gearing arrangement, it will be understood that when the cylinder is rotated slowly the cutting tools will be rotated rapidly and in a direction opposite to the rotation of the cylinder.

65 The cylinder 11 is provided across its

peripheral face with a recess 34 through which extends a rock shaft 35, the ends of which are operatively mounted in the flanges 12 of the cylinder. Mounted in spaced relation upon this rock shaft is a series of 70 grippers 36 which are normally engaged with the surface of the cylinder within the recess 34 by means of spring members 37 which are coiled about the rock shaft and which have their extremities engaging the 75 cylinder as clearly illustrated in Figs. 2 and 3. At one end the rock shaft 35 is provided with a crank 38 which carries a roller 39. Upon a projection 40, which extends upwardly from the end 13 is a cam element 41 80 of arcuate form as shown in Fig. 1. This cam element has inwardly bevelled ends 42. This cam element is supported in the path of the crank supported roller 39, so that under the rotation of the cylinder the grippers 85 will be raised because of the engagement of the roller with the cam element on which it turns, and also so that on the roller's disengagement from the cam element the springs 37 will again actuate the rock shaft 90 and reengage the fingers with the cylinder.

43 denotes an overlay sheet which has a plain side 44 and a coated side 45. When an impression as 46 is made on the plain side of this overlay sheet it will produce a 95 raised portion as 47, more or less pronounced according to the severity of the impression, on the coated side 45 of the sheet. The overlay sheet is applied to the cylinder with its coated side outward and it is attached to the cylinder by engaging an end thereof under the grippers 36. The overlay sheet thus held by the grippers moves and travels with the cylinder, and in order to prevent the overlay sheet from falling 100 away from the cylinder during the downward turn there is provided a series of spaced-apart bands 47' which are mounted upon a rod 48' which is secured in the end members 13. In advance of each of the 105 cutting tools is a brush 48 which is adjustably supported in the frame ends 13. These brushes press on the overlay sheet and force out all air thereunder making it hug the cylinder tightly so that the cutting knives 110 will cut off only the portions of the raised impressions 47 that are raised higher (by too heavy an impression) than the ordinary thickness of the overlay sheet. By means of a proper adjustment of the cutting tools, therefore, the inequalities of the printing form may be compensated for, since the "higher spots" and raised portions on the coated side of the overlay sheet may be cut or sliced off positively and accurately. When 115 the coated overlay sheet has thus been operated on by my improved machine, it is ready to be placed on the packing on the press and the form is ready to print. In the event that the coated overlay sheet does not compensate for 120

125 one overlay sheet does not compensate for 130

the inequalities of the form, it will be observed that an additional overlay sheet or additional overlay sheets may be made in a manner that will be well understood by those familiar with the art.

The solid end frames 13 act as shields against the spreading of the dust resulting from the operation of the cutting tools on the overlay sheets. Additionally in order to prevent the spread of the dust resulting from the cutting operations, I mount within a channel or housing 49 within the hollow base a suction rotor 50 adapted to be driven by a motor 51 and located so that it will influence the dust ground from the overlay sheets and draw the same into the hollow base.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. An overlay cutting machine including a cylinder having support for rotary movement and having a peripheral surface for receiving an overlay sheet thereon; a rotary dressing wheel extending across the face of the cylinder for operating on the overlay sheet; and means within the body of the cylinder inwardly of the peripheral surface thereof for gripping one end of the overlay sheet to the cylinder, substantially as described.

2. An overlay cutting machine including a cylinder having support for rotary movement and having a peripheral surface for receiving an overlay sheet thereon; a dressing wheel having support across the surface of the cylinder to operate on the overlay sheet; and means situated wholly inwardly of the surface of the cylinder for gripping the end of the overlay sheet; substantially as described.

3. An overlay cutting machine including a cylinder having support for rotary movement and having a peripheral surface for receiving thereon an overlay sheet to be dressed; means for pressing the overlay sheet to the surface of the cylinder as it turns therewith; a dressing wheel extending across the surface of the cylinder to operate on the overlay sheet; and means situated wholly inwardly of the surface of the cylinder for gripping the end of the overlay sheet, substantially as described.

4. An overlay cutting machine including a cylinder having support for rotary move-

ment and having a ground peripheral surface for receiving thereon an overlay sheet to be dressed; a dressing wheel arranged to be rotated and applied to the overlay sheet; a gripping device for attaching the overlay sheet to the cylinder and arranged wholly within a recess extending inwardly of the cylinder from said ground surface, and means for operating said gripping device, substantially as described.

5. Means for cutting off portions of impressions on a coated overlay sheet including, in combination, a support for the overlay sheet; a dressing wheel; means for rotating and controlling the application of the dressing wheel to said impressions; and means situated inwardly of the surface of the support for attaching the overlay sheet to the support, substantially as described.

6. In an overlay cutting machine, the combination with end supports, of a cylinder supported for rotary movement between said supports and having a peripheral surface for receiving an overlay sheet thereon; means having adjustment in the ends of the supports extending across the cylinder for operating on the overlay sheet; a gripping device on the cylinder for attaching the overlay sheet thereto; and means on one of said supports for contacting with and operating said gripping device, substantially as described.

7. In an overlay cutting machine, the combination with a cylinder having support for rotary movement and having a peripheral surface for receiving an overlay sheet thereon, of means for securing the overlay sheet to the cylinder beneath the peripheral surface thereof and comprising a recess extending inwardly from said peripheral surface to receive a portion of the overlay sheet; and a spring urged rock shaft operatively arranged within said recess and provided with fingers for gripping the portion of the overlay sheet entered in the recess, substantially as described.

8. In an overlay cutting machine, the combination with a rotary cylinder having a peripheral recess, a rock shaft arranged in said recess, gripping fingers on said rock shaft adapted to secure an overlay sheet on the cylinder, means for causing the rocking of said rock shaft, and means adjustable in relation to the cylinder for operating on the overlay sheet carried by the cylinder, substantially as described.

9. In an overlay cutting machine, the combination of a cylinder having a recess extending inwardly into its body from its peripheral surface, of a shaft arranged in said recess for rocking movement; and means on said shaft adapted to bear on and secure the end of an overlay sheet in said recess, substantially as described.

10. In an overlay cutting machine, the

combination with a cylinder supported for rotary movement and having a peripheral indentation for receiving the end of an overlay sheet therein, of a rockable gripping device arranged in said indentation for securing the end of an overlay sheet in place; an arm on the gripping device projecting from one end of the cylinder; and means arranged to be engaged by said arm by which to rock said gripping device, substantially as described.

In testimony whereof I have signed my name to this specification.

SAMUEL ANDREW McFARLAND.
